Atty.

UNITED STATES PATENT OFFICE.

SIDNEY RICHARDSON, OF HATTON GARDEN, LONDON, ENGLAND.

MACHINERY FOR BEVELING THE EDGES OF GLASS LENSES AND THE LIKE.

Application filed April 4, 1921. Serial No. 458,494.

To all whom it may concern:

Be it known that I, SIDNEY RICHARDSON, a subject of the King of Great Britain, residing at 37-38, Hatton Garden, in the county of London, England, have invented certain new and useful Improvements in or Relating to Machinery for Beveling the Edges of Glass Lenses and the like, of which the following is a specification.

10 This invention relates to machinery for beveling the edges of glass lenses and the like, and has particular reference to automatically-acting apparatus of the kind in which a bevel-edged grinding wheel is employed for making a single or double bevel edge on spectacle lenses. The objects of the present invention are to provide a lens-beveling machine of this type of simplified construction in comparison with apparatus 20 heretofore employed, and by means of which improvements in the quality of the results obtained therewith are attained.

According to the present invention for the beveling of spectacle lenses and the like, 25 there is employed a grinding wheel having a V-shaped or double bevelled edge. It is to be understood that by the expression "V or double bevelled edge" is meant a double bevel which in cross-section is of a male or 30 projecting form, in distinction to a reentrant, grooved, or hollow form.

A feature of this invention, for the production of double bevelled edge lenses, consists in providing for the mechanical movement of the wheel and lens relatively to one another in a direction substantially parallel to the axis of the lens-carrying spindle so as to enable the bevel edges of the wheel to grind successively bevel edges of opposite 40 inclination on the lens. This relative movement of the lens and grinding wheel may be made automatic and of a reciprocating nature so as to enable each bevel edge of the wheel to grind repeatedly but alternately on the periphery of the lens any desired number of times, until the edges of the lens have been ground to the required form and size.

In order that the said invention may be 50 clearly understood and readily carried into effect, the same will now be described more fully with reference to the accompanying drawings, in which:—

Figure 1 is a side view and Figure 2 an 55 edge view of the grinding wheel.

Figure 3 is an elevation of the grinding wheel and lens as arranged for making a single bevel edge on the lens.

Figure 4 is an elevation of the grinding wheel and lens showing the second position 60 of the lens during the production of a double bevel or V edge on the lens.

Figures 5 and 6 are a plan and an end elevation respectively of a lens grinding and beveling machine in accordance with 65 this invention.

Referring first more particularly to Figures 1 to 4, the grinding wheel 1 of stone or other suitable abrasive material has its periphery cut to a V form so as to form bevel 70 edges 2, 3 on either side of the central plane 4 of the wheel. The lens 5 mounted on the rotatable spindle 6 is adapted to be brought into contact with an edge of the wheel and is thereby ground to the required size and 75 shape and at the same time bevelled with either a single bevel edge as shown in Figure 3, or with a double bevel edge as shown in Figure 4. In the latter case the spindle 6 may be so arranged as to transfer the lens automatically from side to side of the bevel edges of the grinding wheel, as will be hereinafter described.

In the lens grinding and beveling machine shown in Figures 6 and 7, the bevel 85 edged grinding wheel 1 is mounted on the shaft 7 and driven by the main driving pulley 8 thereon. The lens 5 carried by the rotatable spindle 9 is fixed in position between pads 10, a tightening screw 11, with a spring adjustment being provided for clamping the lens firmly between the pads. From the shaft 7, power is transmitted by belt pulleys 12 and 13, epicyclic reducing gear in the box 14, and belt pulley 15, to the 90 belt pulley 16, the sizes of the various pulleys and the epicyclic gearing being arranged so that the pulley 16 which drives the spindle 17 has its speed of rotation reduced to the desired fraction of the speed of rotation of the shaft 7. By means of a clutch 18, the pulley 16 can be thrown into or out of driving connection with the spindle 17 as required. The said spindle 17 is provided with a cam device 18^a working in conjunction with a stationary pin 18^b for giving said spindle a reciprocating motion in the direction of its length. Rotation of the spindle 9 is effected by means of a gear wheel 19 meshing with a gear wheel 20 car- 100

ried by the spindle 17, and at the same time the spindle 9 is subjected to the same reciprocating movement as the spindle 17, as the former spindle is mounted on swivel heads 21 carried by the spindle 17. An indicator 22 showing the position of the cam is also provided so that the cam can be brought to the correct position when centering the lens. By means of the plate 23 and adjusting 10 screws 24, the two spindles 9 and 17 can be moved nearer to or further from the grinding wheel 1 as may be found necessary. For bringing the lens into contact with the grinding wheel and retaining the edges of 15 the lens and wheel in contact during the grinding and beveling operation there is employed a spring 25, one end 25' of which is connected with the swivel head 21 while the other end 25" can be attached to a fixed support on the machine as and when required. The desired form and shape imparted to the lens is controlled by means of a template 26, shaped so as to correspond with the final form to which the lens is to be ground; the 20 template 26 is mounted on the same spindle 9 as the lens, and co-acts with a guiding plate 27 having edges bevelled to correspond with those of the grinding wheel, but provided with a protuberant part 28 in place of 25 the sharp edge where the two bevelled planes would normally meet so as to prevent the lens grinding on the line of junction of the two bevel edges of the grinding wheel. The template may however if desired be of 30 any bevel edge form without the protuberance shown in the drawing. By means of a micrometer adjustment 29 the distance between the template 26 and its guiding plate 27 can be adjusted in accordance with 35 the size to which it is desired to grind the lens.

The operation of the machine is briefly as follows:—

The cam 18* is first set relatively to the 40 indicator 22 for causing the correct centering of the lens, and the lens is thereupon inserted in place between the pads 10 on the spindle 9 and clamped in position by the aid of the tightening screw 11. The thickness of the pads 10 depends on the thickness of the particular lens to be treated, and thicker or thinner pads are employed as may be necessary to bring the lens into an accurately central position with regard to the 45 grinding wheels as shown in Figures 5 and 6. The distance between the template 26 and the guiding plate 27 is adjusted by means of the micrometer 29 in accordance with the size to which the lens is to be 50 ground. The grinding and beveling operation can then be proceeded with by causing the clutch 18 to engage with the pulley 16 which is rotated by the driving belts when the machine is running, a double bevelled 55 edge being given to the lens owing to the

reciprocating motion imparted by the cam 18* to the spindle 9 through the swivel heads 21, and the edges of the lens and wheel being brought into contact by attachment of the free end 25" of the spring 25 to its fixed 70 support.

Instead of constructing the machine so that the lens has a forward and backward as well as a rotational movement, the same effect may be secured by arranging for the 75 lens to remain stationary, save for its rotational movement, and for the grinding wheel both to rotate and have a reciprocating motion in the direction of its driving shaft so that the lens is ground and bevelled alternately by first one and then the other 80 edge of the grinding wheel in the same manner as takes place with the arrangement shown in the drawings.

What I claim and desire to secure by 85 Letters Patent of the United States is:—

1. An apparatus for beveling the edges of spectacle lenses and the like comprising, in combination, a grinding wheel having a V or double bevelled edge of male or projecting form, means for mechanically rotating said wheel, means comprising a rotatable swivelling spindle for supporting the lens, a rotary and reciprocatory driving spindle means for imparting rotation and reciprocation from said driving spindle to said lens-carrying spindle, means comprising a cam device for imparting a longitudinal reciprocating motion to said driving spindle, and means for regulating the distance between 90 the axis of rotation of the grinding wheel and the axis of rotation of the lens during the rotation and reciprocation of said lens-carrying spindle. 95

2. An apparatus for beveling the edges 100 of spectacle lenses and the like comprising, in combination, a grinding wheel having a V or double bevelled-edge of male or projecting form, means for mechanically rotating said wheel, means comprising a rotatable swivelling spindle for supporting the lens, means for advancing the spindle towards the wheel, a rotary and reciprocatory driving spindle for actuating the lens-carrying spindle, means comprising a 105 cam device for imparting a longitudinal reciprocating motion to said driving spindle, gearing connecting the lens-carrying spindle and the driving spindle for rotating said lens-carrying spindle, connecting means between the said lens-carrying spindle and said driving spindle whereby said lens-carrying spindle is permitted to swivel and has imparted to it the longitudinal reciprocating motion of the driving spindle, and means 110 for regulating the distance between the axis of rotation of the grinding wheel and the axis of rotation of the lens during the rotation and reciprocation of said lens-carrying spindle. 115

3. An apparatus for beveling the edges of spectacle lenses and the like comprising, in combination, a grinding wheel having a V or double bevelled edge of male or projecting form, means for mechanically rotating said wheel, means comprising a rotatable swivelling spindle for supporting the lens, a rotary and reciprocatory driving spindle for actuating the lens-carrying spindle, means comprising a cam device for imparting a longitudinal reciprocating motion to said driving spindle, gearing connecting the lens-carrying spindle and the driving spindle for rotating said lens-carrying spindle, connecting means between the said lens-carrying spindle and said driving spindle whereby said lens-carrying spindle is permitted to swivel and has imparted to it the longitudinal reciprocating motion of the driving spindle, and means for regulating the distance between the axis of rotation of the grinding wheel and the axis of rotation of the lens during the longitudinal displacement of the lens-carrying spindle whereby both edges of the lens are ground during one forward or backward rotation and reciprocation of said lens-carrying spindle, said regulating means comprising a template carried by the lens-carrying spindle and a guiding plate bevelled to correspond with the bevelled edges of the grinding wheel and co-acting with said template whereby the extent of the swivelling movement of said lens-carrying spindle during its longitudinal movement is regulated to the required degree.

4. An apparatus for beveling the edges of spectacle lenses and the like comprising, in combination, a grinding wheel having a V or double bevelled-edge of male or projecting form, means for mechanically rotating said wheel, means comprising a rotatable swivelling spindle for supporting the lens, means for advancing the spindle towards the wheel, a rotary and reciprocatory driving spindle for actuating the lens-carrying spindle, means comprising a cam device for imparting a longitudinal reciprocating motion to said driving spindle, gearing connecting the lens-carrying spindle and the driving spindle for rotating said lens-carrying spindle, connecting means between the said lens-carrying spindle and said driving spindle whereby said lens-carrying spindle is permitted to swivel and has imparted to it the longitudinal reciprocating motion of the driving spindle, and means for regulating the distance between the axis of rotation of the grinding wheel and the axis of rotation of the lens during the rotation and reciprocation of the lens-carrying spindle whereby both edges of the lens are ground during one forward or backward longitudinal movement of said lens-carrying spindle, said regulating means comprising a template carried by the lens-carrying spindle and a guiding plate bevelled to correspond with the bevelled edges of the grinding wheel and co-acting with said template whereby the extent of the swivelling movement of said lens-carrying spindle during its longitudinal movement is regulated to the required degree.

5. An apparatus for beveling the edges of spectacle lenses and the like comprising, in combination, a grinding wheel having a V or double bevelled edge of male or projecting form, means for mechanically rotating said wheel means comprising a rotatable swivelling spindle for supporting the lens, a rotary and reciprocatory driving spindle for actuating the lens-carrying spindle, means comprising a cam device for imparting a longitudinal reciprocating motion to said driving spindle, gearing connecting the lens-carrying spindle and the driving spindle for rotating said lens-carrying spindle, connecting means between the said lens-carrying spindle and said driving spindle whereby said lens-carrying spindle is permitted to swivel and has imparted to it the longitudinal reciprocating motion of the driving spindle, and means for regulating the distance between the axis of rotation of the grinding wheel and the axis of rotation of the lens during the rotation and reciprocation of the lens-carrying spindle whereby both edges of the lens are ground during one forward or backward longitudinal movement of said lens-carrying spindle, said regulating means comprising a template carried by the lens-carrying spindle and a guiding plate co-acting with said template, said guiding plate being bevelled to correspond with the bevelled edges of the grinding wheel and provided with a protuberance between the bevelled planes.

6. An apparatus for beveling the edges of spectacle lenses and the like comprising, in combination, a grinding wheel having a V or double bevelled-edge of male or projecting form, means for mechanically rotating said wheel, means comprising a rotatable swivelling spindle for supporting the lens, means for advancing the spindle towards the wheel, a rotary and reciprocatory driving spindle for actuating the lens-carrying spindle, means comprising a cam device for imparting a longitudinal reciprocating motion to said driving spindle, gearing connecting the lens-carrying spindle and the driving spindle for rotating said lens-carrying spindle, connecting means between the said lens-carrying spindle and said driving spindle whereby said lens-carrying spindle is permitted to swivel and has imparted to it the longitudinal reciprocating motion of the driving spindle, and means for regulating the distance between the axis of rotation of the grinding wheel and the axis of rotation of the lens during the rotation and reciprocation of the lens-carrying spindle whereby both edges of the lens are ground during one forward or backward longitudinal movement of said lens-carrying spindle, said regulating means comprising a tem-

of the lens during the rotation and reciprocation of the lens-carrying spindle whereby both edges of the lens are ground during one forward or backward longitudinal movement of said lens-carrying spindle, said regulating means comprising a template carried by the lens-carrying spindle and a guid-

ing plate co-acting with said template, said guiding plate being bevelled to correspond with the bevelled edges of the grinding wheel 10 and provided with a protuberance between its bevelled planes.

SIDNEY RICHARDSON.
